(57) **CLAIM**

The ornamental design for a boot cover, as shown and described.

DESCRIPTION

The present application is related to commonly assigned U.S. patent applications Ser. Nos. 29/616,009, 29/616,018, 29/616,023 and 29/616,027, all filed Sep. 1, 2017.

FIG. 1 is a front right perspective view of a boot cover showing my new design, with an environmental boot; FIG. 2 is a front elevational view thereof.

FIG. 3 is a rear elevational view thereof.

FIG. 4 is a right elevational view thereof.

FIG. 5 is a left elevational view thereof.

FIG. 6 is a top plan view thereof; and,

FIG. 7 is a bottom plan view thereof.

The broken lines depicting a boot represent environment that forms no part of the claimed design.
